CONVECTOR

Robert S. Wentworth, Johnstown, Pa., assignor
to National Radiator Corporation, Johnstown, Pa., a corporation of Delaware

Application March 25, 1932. Serial No. 601,194

14 Claims. (Cl. 257—136)

This invention relates to a space or room heater, and more particularly to that type of indirect heater generally termed a "radiator", and is especially for this type of heater adapted to be enclosed within a cabinet open at the top and the bottom and so disposed as to set up convective currents. These heaters are generally termed "convectors".

As explained in my copending application Serial No. 513,883, filed February 6, 1931, a convector, to function efficiently, should be constructed so as to provide for a relatively short air flow in contact with the convector. The reason for this is that the greater the differential in the temperature of the air and of the convector, the greater is the rate of heat transfer from the convector to the air. As the temperature of the air rises, the rate of heat transfer diminishes. Radiation is figured on the basis of the rate of heat transfer per pound of metal employed. Where the convector is so constructed that the air flows in contact with the convector for a relatively great distance, the temperature of the air in the last portion of the flow is much higher than the temperature of the air initially. The rate of heat transfer is therefore proportionately less in the latter portion of the travel of the air, with the result that the portion of the convector across which the air last flows has a relatively low efficiency per pound of metal employed.

Moreover, in a convector it is desirable to have a considerable amount of extended area in the form of heat radiating or dissipating fins. Where the convector is made of cast iron, the problem of casting restricts the number of fins and their extent and minimum thickness.

The present invention provides a convector adapted to be formed from cast iron in which the air will have relatively short but turbulent passage and wherein the heat radiating fins are so disposed as to give a large amount of extended area in proportion to the prime surface of the convector and considering the limitations that the problem of casting impose.

The invention may be readily understood by reference to the accompanying drawings, in which

Figure 1 is an end view of a convector assembly embodying my invention and wherein the outline of the cabinet in which the convector is contained is conventionally shown;

Figure 2 is a front elevation of the convector, only a few of the heat radiating fins, however, being shown;

Figure 3 represents a transverse vertical section in the plane of line III—III of Figure 2;

Figure 4 is a similar section in the plane of line IV—IV of Figure 2;

Figure 5 is a view similar to Figure 2 showing the manner in which the units may be coupled together in end-to-end relation:

Figure 6 is a top plan view of the arrangement shown in Figure 2 and

Figures 7 and 8 are diagrammatic views illustrating the advantage of using heat dissipating fins or barrels of small diameter over barrels of large diameter.

Referring first to Figure 1 of the drawings, this figure shows the assembly of the convector, particularly with relation to the cabinet in which it is retained. The cabinet may comprise a metal enclosure, or may be built into the wall of a building. A represents the floor line of the cabinet; B the back wall; and C is the front panel. There is a vertical chamber D between the back and front walls B and C. At the floor line is an air inlet opening E and at the top of the cabinet the chamber D is open, as indicated at F.

The convector assembly is inclined at an angle across the chamber D. I have shown the chamber D conventionally and of a dimension which would be the minimum dimension for radiation of this type. The chamber might be considerably wider, depending upon the provision made for radiation, in which case the convector would slope to even a greater extent from the vertical position.

The convector itself is formed of two parts, the lower one of which is designated 2 and the upper one is designated 3. Part 2 is an integral casting and part 3 is an integral casting, the two parts being of the same construction, but part 3 being turned upside down with respect to part 2.

The section 2 has a main horizontal barrel portion 4 at the bottom thereof, and above this is a series of similar but smaller horizontal barrels 5. The horizontal barrels all open into vertical barrels 6 at each end of the section, and between the end barrel 6 at regular intervals are other vertical barrels 7. Cast integrally with the barrels are vertically extending heat radiating fins 8. At the lowermost corners of this section are offset connector portions 9, the arrangement of which may be best seen by reference to Figure 3. These connector portions 9 are offset to one side of the center line of the several barrels and the center line of the connector forms an angle to the center line passing through the several barrels. At the bottom of each section in the end wall thereof is a boss 10 in which a nipple port may be formed when it is desirable to have a connection leading

105

110

into the end of the section rather than into the bottom connector 9. The boss 10 is normally cast with a closed wall and where it is desirable to have an open port the casting is cut away. On 5 the side face of the section 2 at each corner is a nipple boss 12 having an opening therethrough. In the uppermost corners of the section 2 are connector portions 13 having nipple bosses 14 with ports therethrough, these bosses and ports being 10 on the side face of the section.

The upper section 3, as previously stated, is of the same construction as the lower section 2, but it is reversed and upside down with respect to the lower section 2. When the two sections are 15 reversed and put together in this way the nipple ports 14 of the upper section 3 register with the nipple ports 12 of the lower section 2. Likewise, the nipple ports 14 of the lower section 2 register with the nipple ports 12 of the upper section 3.

20 The lowermost barrel 4 of the section 2 is the lowermost barrel of the assembly, while the corresponding large barrel 4 of the upper section is the highest part of the assembly. When the two sections are put together in this fashion the horizontal barrels 5 of the lower section 2 are staggered with respect to the corresponding barrels of the upper section 3. For securing the sections together in this relation the section 2 is provided with threaded lugs or bosses 15 at the top thereof 25 adjacent each end of the section, and it is provided at 16 with webs having bolt holes therein. The section 3 of course has correspondingly located bosses and bolt holes and when the sections are put together the bolt holes of one section 30 register with the threaded bosses of the other, allowing the two sections to be tightly bolted together by the bolts 17 as shown in Figure 6.

40 Preferably, the sections are made relatively short so that they can be arranged in multiples in end-to-end relation according to the length of the cabinet.

45 In connecting the sections together in end-to-end relation, as shown in Fig. 1, the nipple ports in the bosses 10 of the abutting ends of the sections are cut through. The sections are forced together with a push nipple as will be readily understood by those skilled in the art. For rigidly holding the assembly together the sections are provided at the top and bottom at each end thereof 50 with ears or lugs 18. Short tie bolts 19 pass through the lugs 18 adjacent the abutting ends of the sections. Only two nipples are required to connect two units comprising four sections. The nipple ports 10 might of course be cast all the 55 way through and subsequently supplied with screw plugs and then, to join the sections in end-to-end relation, the plugs would be removed at the abutting ends of the sections.

60 The arrangement of several vertical and horizontal columns in each of the two sections of a unit is highly desirable because without the intermediate barrels 7 the steam would tend to rise up one of the vertical barrels 6, flow along the top barrel, and down the other end barrel, and trap air between the ends of the intervening barrels 5 and in the lowermost barrel 4. However, through the provision of the several vertical barrels 7, intermediate the end barrels, the circulation is set up in such manner as to draw all of the 65 entrapped air out of all of the horizontal barrels.

70 The advantage of using two sections in superimposed relationship instead of using single barrels of relatively greater capacity resides in the fact that there may be a greater amount of efficiently disposed extended area in proportion to

the amount of prime area and less weight of metal in the extended area. The reason for this is best explained by reference to Figs. 7 and 8. In Figure 8 I have shown a barrel M having integral heat radiating fins L thereon. From the standpoint of casting, the distance between the fins should not be materially less than the height of the fins. In other words, the dimension l should be about the same as the distance h. This relation holds true irrespective of the diameter of the barrel M. In Figure 7 I have shown two barrels of different diameters; the large one is designated X and the smaller one Y. Each is shown as being provided with an integral cast fin, these fins being designated x and y, respectively. The height of the fin y is the same as the height of the fin x, and as explained in connection with Figure 8, the spacing between fins should be about equal to the height. The area of the fin y proportionately to the diameter of the tube Y is much greater than the area of the fin x with relation to the diameter of the tube X. The smaller tube Y therefore has a greater extended area in proportion to the prime area than has the tube X.

80 Referring again to Figure 1, the chamber D is of a fixed width. The size of the heating unit which it will contain is necessarily limited.

85 Applying the principle explained in connection with Figures 7 and 8, it will be seen that a greater amount of extended area with respect to the prime area can be placed in the limited space provided by the cabinet by the use of two sections having small barrels instead of using a single section having relatively larger barrels.

90 In addition to this, in making a cast metal fin 110 the pattern has to have a certain slope or taper in order to enable it to be lifted out of the sand mold. The fins cannot be cast on a commercial basis below a minimum thickness. Taking, for example, two fins each of this minimum thickness 115 at the tip, and one two inches high, and one one inch high, each must have the same taper so that the pattern can be pulled clear of the mold. The two-inch fin must, therefore, be relatively thicker at its base than the one-inch fin. This means 120 that the higher fin has a greater weight of metal per foot of extended area than has the shorter fin.

95 The present invention, therefore, enables the use of shorter fins spaced closer together, giving a greater area of extended surface with relation to the area of the prime surface and with a less weight of metal per unit area of extended surface than is obtainable using larger barrels with longer fins. The invention gives in the joining of two sections having small barrels the effect of substantially continuous fin surface.

100 In a convector radiator it is desirable to have a short air travel over the surface of the convector with a relatively large amount of area to contact with the air. This is obtained in the present invention. The air entering the cabinet in which the convector is housed through the port E rises along the underside of the convector unit, and passes diagonally through the convector, as indicated by the arrows. The diagonal passage through the convector gives a relatively short air travel. As previously pointed out, the invention gives a relatively large extended area per unit of prime area. The invention thus incorporates in a cast metal structure a degree of 115 efficiency which has heretofore been approached only in assembled sheet metal structures disposed in a horizontal position. As the depth of the cabinet is increased, permitting a greater sloping of the convector unit, the greater is the effi- 120 ciency.

ciency of the section because the travel of the air is more nearly vertical and is deflected less from the true vertical flow. The drawing, Figure 1, therefore shows the convactor disposed in its least 5 advantageous position insofar as efficiency is concerned, but in the position in which it occupies the least width of floor space or depth of cabinet space.

It is desirable that the lowest barrel of the 10 unit, because it has to handle the steam flow and condensate from both sections, be larger than the other barrels of the assembly, and this arrangement is obtained because the lowermost barrel 4 is of larger diameter. It is also desirable that 15 the highest part of the convactor be of relatively large capacity in order to facilitate the air flow to this portion of the convactor to enable the air to be drawn out through a caulk (not shown). The present invention provides this advantage 20 through the reversal of one section with respect to the other, and incidentally, secures also the staggering of the two series of horizontal barrels.

The arrangement of the offset connector portions 25 9 in the bottom of the section 2 and in the top of the section 3 is desirable from the standpoint of making connections to the convactor. Moreover, the steam intake pipe can enter the bottom of the lower section or the top of the upper 30 section, enabling the convactor to be adapted to all types of piping systems which are used for heating plants. Those connector portions which are not required to be used are plugged.

While I have described the invention in detail, it will be understood that this is by way of illustration and that various changes and modifications may be made in the construction shown within the contemplation of my invention and under the scope of the following claims.

40 I claim:

1. A convactor comprising a cast metal unit having a series of horizontal barrels and a series of vertical barrels, vertically extending fins on the horizontal barrels, and an enclosure around the unit having an opening below the unit and an opening above the unit and providing a flue intermediate the openings, the convactor being inclined from a vertical position across the flue.

2. A convactor comprising a cast metal unit having a series of horizontal barrels and a series of vertical barrels, vertically extending fins on the horizontal barrels, and an enclosure around the unit having an opening below the unit and an opening above the unit and providing a flue intermediate the openings, the convactor being inclined from a vertical position across the flue, the lowermost barrel of the convactor being of greater diameter than the other barrels.

3. A convactor comprising a cast metal unit having a series of horizontal barrels and a series of vertical barrels, vertically extending fins on the horizontal barrels, the convactor being inclined from a vertical position, the lowermost barrel of the convactor being of greater diameter than the other barrels, and connector portions at each end of the section opening into the lowermost barrel, said connector portions being laterally offset from the plane of the central line of the several barrels.

4. A convactor comprising a cast metal unit having a series of horizontal barrels and a series of vertical barrels, vertically extending fins on the horizontal barrels, the convactor being inclined from a vertical position, the lowermost barrel of the convactor being of greater diameter

than the other barrels, connector portions at each end of the section opening into the lowermost barrel, said connector portions being laterally offset from the plane of the central line of the several barrels, and a second section superimposed on the first and having ports communicating therewith, the second section being inverted with respect to the first.

5. A convactor comprising two series of horizontally extending barrels connected by vertical barrels, the horizontal barrels of one series being staggered with reference to those of the other series, heat radiating fins on the horizontal barrels, and an enclosure for the convactor opening below and above the convactor and providing a flue intermediate the openings, the convactor being disposed at an angle across the flue and between the upper and lower openings.

6. A convactor comprising two series of horizontally extending barrels connected by vertical barrels, the horizontal barrels of one series being staggered with reference to those of the other series, integrally cast vertically extending heat radiating fins on the barrels, and an enclosure for the convactor opening below and above the convactor and providing a flue intermediate the openings, the convactor being disposed at an angle across the flue and between the upper and lower openings.

7. A convactor comprising a section having a series of communicating horizontal barrels, said barrels having heat radiating fins thereon, a second section superimposed on the first and similar to the first, the barrels of the second section being staggered with relation to those of the first, and communicating ports on the two sections.

8. A convactor comprising a section having a series of communicating horizontal barrels, said barrels having heat radiating fins thereon, a second section superimposed on the first and similar to the first, the barrels of the second section being staggered with relation to those of the first, and communicating ports on the two sections, the two sections comprising a unit which is inclined from a vertical plane.

9. A convactor comprising a section having a series of communicating horizontal barrels, said barrels having heat radiating fins thereon, a second section superimposed on the first and similar to the first, the barrels of the second section being staggered with relation to those of the first, and communicating ports on the two sections, the two sections comprising a unit which is inclined from a vertical plane, the lowermost barrel of the first section being of larger diameter than the other barrels, the uppermost barrel of the second section being of larger diameter than the other barrels.

10. A convactor unit comprising two sections of similar construction arranged in superimposed relation, one of which is inverted with respect to the other, the sections having registering ports therein, means for securing the sections together, the sections having a series of horizontal barrels which communicate with each other through connecting barrels, the series of barrels being provided with vertically extending fins, the horizontal barrels of one series being staggered with relation to those of the other.

11. A convactor comprising an integral cast metal section having a series of horizontal barrel portions, the lowermost of which is of larger diameter than the remaining portions, vertical barrel portions connecting the horizontal bar-

rel portions, said section having connector ports on one face thereof adjacent each corner thereof, a similar section superimposed on said first section but inverted with respect to the first section and having horizontal barrel portions thereon staggered with respect to those of the first, the ports in the faces of the two sections registering, and pipe connector portions on each section.

12. A convector assembly comprising two units in end-to-end relation, each unit comprising two sections of similar construction but one of which is inverted with respect to the other, each section having a plurality of horizontal barrel portions connected by vertical barrel portions, the sections of each unit having communicating ports, one section of each unit being arranged above the other section of the same unit, the uppermost portions of the upper sections of the respective units being in direct communication, and the lowermost portions of the lower sections of each unit being in direct communication.

13. A convector assembly comprising two units in end-to-end relation, each unit comprising two sections of similar construction but one of which is inverted with respect to the other, each section having a plurality of horizontal barrel portions connected by vertical barrel portions, the sections of each unit having communicating ports, one section of each unit being arranged above

30

the other section of the same unit, the uppermost portions of the upper sections of the respective units being in direct communication, and the lowermost portions of the lower sections of each unit being in direct communication, the horizontal barrels of the upper units of each section being staggered with relation to those of the lower unit, the entire assembly being inclined from a vertical plane.

14. A convector assembly comprising two units in end-to-end relation, each unit comprising two sections of similar construction but one of which is inverted with respect to the other, each section having a plurality of horizontal barrel portions connected by vertical barrel portions, the sections of each unit having communicating ports, one section of each unit being arranged above the other section of the same unit, the uppermost portions of the upper sections of the respective units being in direct communication, and the lowermost portions of the lower sections of each unit being in direct communication, the horizontal barrels of the upper units of each section being staggered with relation to those of the lower unit, the entire assembly being inclined from a vertical plane, each section of each unit having a plurality of vertically extending heat radiating fins thereon.
